United States Patent Office

Des. 221,419

Patented Aug. 17, 1971

221,419

CONTAINER FOR A FOOD SPREAD

Miles R. Grove, New York, N.Y., assignor to Lever Brothers Company, New York, N.Y.

Filed Apr. 27, 1970, Ser. No. 22,943

Term of patent 14 years

Int. Cl. D9—99

U.S. Cl. D9—220

FIG. 1

FIG. 2

FIG. 3

FIG. 1 is a developed view of the side wall of a container for a food spread showing my new design;

FIG. 2 is a top perspective view of the container for a food spread of FIG. 1; and

FIG. 3 is a bottom view thereof.

I claim:

The ornamental design for a container for a food spread, as shown.
